18 Claims. (Cl. 112—21)

1

This invention relates to paper sheet handling machines such as book-stitching machines in which the individual paper sheets (or signatures) are placed upon a saddle or supporting table and are then carried to a position where an operation, e. g. a stitching operation, is performed upon them.

More particularly, although not exclusively, the invention relates to book-stitching machines of the swinging saddle type where the sheets (or signatures) to be stitched are placed upon a saddle-shaped supporting table adapted to swing up and down to receive the sheets when in its lowered position and to bring them up to and beneath the stitching mechanism upon reaching its uppermost position. The placing of the sheets upon the saddle may be effected manually or in an automatic manner such as by means of a forwarding or throwing movement with the aid of rollers, swingers or slides.

With such machines, particularly when working at the high speeds attained by modern forms thereof, difficulty is experienced in obtaining accurate registration of the various sheets, one with the other. For example, when different qualities of paper are to be included within a single stitched book or pad, it is found that the head ends of the individual sheets are not stitched exactly in register one with the other as desired but that, after stitching they assume a staggered relationship. With high speed operation the ordinary fixed lays (adjustable to different sized sheets) are no longer sufficient because on the one hand there is rebound and thus defective registration due to the very rapid lateral feed of the sheets on to the saddle when the latter is in the sheet-receiving position, and on the other hand the sheets readily slip out of position while the saddle is being moved into the stitching position, with the result of defective stitching as well as frequent needle fracture.

One object of the invention, therefore, is to provide an improved method of sheet-registration which avoids the difficulties hitherto encountered and which includes the steps of bringing the delivered sheet (or signature) into registration against a stop and then holding said sheet in such registered position during its conveyance to the position where the next operation is performed, e. g. the stitching of the sheet.

Another object of the invention is to provide sheet-registering mechanism comprising a sheet-supporting and conveying table, a registering stop upon said table, means for bringing a sheet (or signature) received upon said table into abut-

2

ment with said stop and clamping means operable to maintain said sheet in its registered position against such stop during subsequent movement of said table.

5 A further object of the invention is to provide improved sheet-registering mechanism for a book-stitching machine of the swinging saddle type and comprising a registering stop upon said saddle, means for moving the sheet into registered position against said stop, a clamping lever movable into and out of clamping engagement with said sheet in its registered position and cam mechanism controlling the movement of said clamping lever and operated during movement of the saddle from its sheet-receiving position to its sheet-stitching position to cause movement of the clamping lever into its sheet-clamping position.

The above and further objects and features of the invention will be better understood from the 20 accompanying detailed description of a number of preferred embodiments when taken in conjunction with the appended drawings. In these drawings:

25 Fig. 1 is a side elevational view of a thread book-stitching machine of the swinging saddle type and embodying the invention;

Fig. 2 is a front elevational view of the machine shown in Fig. 1;

30 Fig. 3 is a front edge view of part of the sheet-supporting table of the swinging saddle shown in Figs. 1 and 2, drawn to an enlarged scale and shown provided with sheet-registering mechanism adapted for handling sheets whose head ends are arranged at the trailing ends of the sheets as they are delivered to the table;

Fig. 4 is a plan view of the table part shown in Fig. 3;

Fig. 5 is a sectional elevation of the sheet stop 40 device of the table shown in Figs. 3 and 4, being taken on the line V—V of Fig. 4 and drawn to a still further enlarged scale and showing the device in the open or non-gripping position;

Fig. 6 is a similar view to Fig. 5 showing the 45 position when the sheet is gripped by the stop device;

Fig. 7 is a view similar to Fig. 3 showing a modified construction suitable for use with sheets having their head ends leading in the direction 50 of delivery of the sheets to the table;

Fig. 8 is a plan view of the modified arrangement of Fig. 7;

Fig. 9 is an enlarged sectional view of similar character to Fig. 5 taken on the line IX—IX 55 of Fig. 8 and showing the stop construction em-

ployed in the arrangement of Figs. 7 and 8 when in the open position;

Fig. 10 is a view of the construction shown in Fig. 9 when in the closed position;

Fig. 11 is a fragmentary view of part of Fig. 2 as modified for use with the arrangement shown in Figs. 7 to 10;

Fig. 12 is a side elevation of a modified form of thread book-stitching machine also embodying the invention;

Fig. 13 is a front elevational view of the machine shown in Fig. 12;

Figs. 14 and 15 are enlarged sectional and plan views respectively of the sheet stop and registering device employed in the arrangement shown in Figs. 12 and 13 and when in the rest position, Fig. 14 being a view on the line XIV—XIV of Fig. 15;

Fig. 16 and 17 are similar views to Figs. 14 and 15 showing the device in the working position, Fig. 16 being a view on the line XVI—XVI of Fig. 17; while

Fig. 18 to 22 are detail views of various parts of the device shown in Figs. 12 to 17, Fig. 22 being a sectional view taken on the line XXII—XXII of Fig. 17.

Referring first to the construction shown in Figs. 1 to 6 it will be seen that the machine generally follows the usual construction of swinging saddle type book or signature stitching machines in that it comprises a saddle having supporting arms 10 and 11 mounted at their lower ends upon a shaft 12 journalled in fixed side frame members 13 and 14. The arms 10 and 11 carry a sheet-supporting table 15 at their upper ends. This table is adapted to be swung in known manner from the position shown in Fig. 1, where sheets (or signatures) are fed thereto, to a position where the table and the sheet or signature thereon is located immediately beneath the needles of the stitching mechanism indicated generally by the reference numeral 16 where the sheet (or signature) is stitched to the remainder of the book pad carried upon the table 17. After such stitching operation the table 15 is returned to the original position shown in Fig. 1 to receive a fresh sheet or signature, the previously stitched sheet being automatically withdrawn from the table during such return movement by its attachment to the remainder of the book pad.

The stitching mechanism 16, which may as indicated be provided with backing strip feeding mechanism 18, may be of any known or convenient form and since it forms no part of the present invention will not be further described.

The swinging movement of the arms 10, 11 and the table 15 is effected in usual manner by the engagement of cam follower rollers 19 carried by extensions 20 of the arms 10, 11, within cam grooves 21 of cam discs 22 rigidly secured to the main drive shaft 23, which shaft is journalled in the side frames 13 and 14 of the machine.

The sheet supporting table 15 has, at its left-hand side (Figs. 2, 3 and 4), a bar 24 slidably mounted therein. This bar which is preferably arranged with its upper surface flush with the upper surface of the table 15 is disposed parallel with the apex edge 25 of the latter and has a roller 26 pivotally mounted at its leftward end. This roller is urged by a spring 27 (Fig. 4) into engagement with the contoured surface of a cam 28 (Figs. 1 and 2) secured to a fixed part of the machine frame. A sheet stop device 29 for the left-hand side of the table is secured to the slide bar 24 in a manner permitting adjustment of its position if desired.

A further slide bar 30 is mounted upon the underside of the sheet-supporting table 15 for movement parallel with the apex edge 25 and the bar 24. This further slide bar 30 carries a roller 31 at its left-hand end (Figs. 2, 3 and 4) for engagement with the forked end of a lever 32 which is pivotally mounted at 33 upon the saddle-supporting arm 10 and has its opposite end provided with a ball 34. This ball 34 is urged, by a spring 35 connected between the arm 10 and the lever 32, into contact with a stationary cam 36 secured to the side frame member 13.

The slide bar 30 has an arm 37 secured thereto with the aid of a clamping screw 38 in a manner permitting adjustment of the position of such arm longitudinally along the bar. The major portion of the arm 37 is disposed beneath the table 15, but its upper end passes through a slot 49 in the table and has a second stop device indicated generally at 39 secured thereto. This stop device which co-operates with the right-hand edge of the sheet (Figs. 2, 3 and 4) is adjustable as to its position relative to the table 15 and to the other stop device 29, by reason of the adjustability of the arm 37, for accommodating the mechanism to various sizes of sheets.

The stop device 39 (shown more particularly in Figs. 5 and 6) comprises a wedge-shaped block 41 secured to the arm 37 by a screw 42. Clamped between the block 41 and the arm 37 and held by said screw 42 is a leaf spring 43 which is shaped to extend upwardly above the inclined surface 41a of the block 41 and terminates in a head 44 overhanging the left-hand edge 41b of said block. This head 44 carries a ball 45 secured in a manner permitting its rotation but preventing its withdrawal or displacement. The lowermost portion of the ball is arranged to project about 1 mm. below the lower surface of the head 44. The latter is chamfered as at 46 to facilitate the passage of a sheet edge therebeneath in a manner hereinafter described. A clamping lever 47 is pivotally mounted upon a pin 48 carried in ears extending from the arm 37. This clamping lever which lies within the slot 49 carries a roller 49 disposed opposite the ball 45 and journalled upon a pin 50 arranged parallel with the slot 49. The lever 47 is engaged by a compression spring 51 seated within a recess of the block 41 and acting to urge the lever downwardly to bring a shoulder 52 thereof into engagement with a side surface of the arm 37.

In the slot 49, just to the left of the block 41 and arm 37 a cam member 53 is secured by means of a bolt 54 and a clamping plate 55, the latter and the edges of the slot 49 being suitably shaped, e. g. by chamfering or by stepping to permit the upper surface of the plate 55 to lie flush with the upper surface of the table 15 and at the same time to allow adjustment of the position of the cam member along the slot 49 in accordance with the adjusted position of the arm 37 and block 41. The cam member 53 comprises an arm 56 projecting towards the block 41 and provided with a stepped upper surface 57.

The operation of the mechanism above described is as follows:

The sheet (or signature) S which is to be stitched is introduced (in opened condition) in known manner on to the sheet-supporting table 15 of the stitching saddle in the direction of the arrow b (i. e. from the right-hand side, Figs. 2 and 3) and with its head end trailing or towards the right-hand side of the table 15. Such delivery may be effected in any known or convenient man-

ner, e. g. by hand or automatically for instance by a feeding arrangement, as shown in Figs. 1 and 2 and comprising a feed table 58 and co-operating feed rollers 59 and 60.

During its passage on to the table 15 the sheet S slides over the stop device 39 by riding up the leaf spring 43 and over the block 41 and finally engages the other stop device 29 by its tail end. The arms 10, 11 now commence their rocking movement in the direction of the arrow c (Fig. 1) towards the position where the table 15 and the sheet S thereon are positioned beneath the stitching mechanism 16.

During such movement the roller 26 travels along the cam 28 and is moved towards the right (Figs. 2, 3 and 4) whereby the bar 24 together with the stop device 29 and the sheet S in contact with the latter are also moved towards the right. By such movement the head end of the sheet is brought up against the block 41 of the stop device 39, entering as it does so, beneath the ball 45.

Immediately such movement of the sheet has been effected, the stop device 39 is then moved in a leftward direction by reason of the rocking movement imparted to the lever 32 by the engagement of its ball end 34 with the cam 36 during the swinging-in movement of the arms 10, 11. Simultaneously the other stop device 29 is also moved leftward (Figs. 2, 3 and 4) by reason of the contour of the cam 28 so that it does not impede the leftward movement of the sheet S and eventually reaches a position clear of the left-hand edges of the sheet. The sheet can, therefore, be flat upon the table 15 with its fold seated upon the edge 25.

During the leftward movement of the stop device 39 the head end of the sheet S is in engagement with the surface 41b of the block 41 and is moved thereby. The clamping lever 47 now slides upon the stepped upper surface 51 of the arm 56 whereby the said lever and the roller 49 carried thereby are lifted to effect clamping of the head end of the sheet S against the ball 45. Such clamping effectively prevents any displacement of the sheet S in the longitudinal direction of the table 15, i. e. laterally of the machine. The sheet S is thus effectively held in its proper registered position upon the table 15 and is retained in such position as the arms 10, 11 continue to move upwardly into the stitching position where the said sheet is stitched by the mechanism 16. Subsequently, when the arms 10, 11 again move downwardly, the sheet S is withdrawn from between the ball 45 and roller 49 by a movement transverse to that by which it was originally fed, which withdrawal is readily permitted even although the clamping lever 47 is still held raised, by reason of the disposition of the pin 59 carrying the roller 49 in a direction transverse to that of the withdrawal movement of the sheet. Upon the return of the arms 10, 11 and the table 15 to their original lowermost position, the various parts are automatically returned to their initial positions in readiness for the feeding of the next sheet and the repetition of the above-described cycle of operation.

Figs. 7 to 11 show a modified form of the embodiment previously described in connection with Figs. 1 to 6 and adapted for use when the head ends of the sheets are leading in the direction of delivery thereof to the table and accordingly in the arrangement shown have to be registered upon the left-hand side of the sheet-supporting table of the stitching saddle. In this modified

construction the construction of the machine generally is similar to that previously described but in this instance the sheet-supporting table 15 is provided with a left-hand stop device 61 and a right-hand stop device 62.

The stop device 61 comprises a block 63 bolted to the table and provided with apertures slidably receiving two rods 64 riveted within a movable block 65 provided with a projecting sheet guide flap 72. Compression springs 66 surround each of these rods, being located between the blocks 63 and 65 so as to urge the block 65 towards the right (Figs. 7 and 8) until enlarged end-pieces 66a on each of the rods bear against the left-hand face of the block 63.

The block 65 has a lug 65a thereon (Figs. 9 and 10) receiving a pin 67 for pivotally mounting a clamping lever 68 provided with a roller 69 carried by a pin 70 in similar manner to the roller 49 of the previous clamping lever 47. Mounted above the roller 69 for co-operation therewith is a ball 71 carried in a head 72 secured to one end of a blade spring 73 secured at its other end to the block 63. The clamping lever 68 is urged downwardly by a spring 74 located within a recess in the block 63 so that its right-hand end rests upon the lower surface of a channel 75 formed along the length of a thrust bar 76 which is slidably mounted in the table 15 in similar manner to the bar 24 of the previous embodiment. This bar 76 is provided with a roller 77 urged by means of a spring 78 in the direction of the arrow d to contact the contoured face of a stationary cam 79 secured to the fixed member of the machine frame (Fig. 11).

Adjustably mounted upon the bar 76 is a block 80 provided with a bore housing a compression spring 81 operative upon the enlarged end of a sliding bolt 82 to urge the latter towards the right 40 through a guide aperture in a cover plate 83 secured to the block 80. The outer end of such bolt which passes through said guide aperture is reduced and is adapted to engage the left-hand face of the movable block 65 in a manner hereinafter described. The block 80 is secured in its adjusted position upon the bar 76 by means of a screw 84 and a clamping plate 85. This latter plate is provided with a chamfered lower surface 86 at its right-hand end for co-operation with an extension 87 of the clamping lever 68.

The right-hand stop device 62 comprises an abutment block 88 mounted upon the free end of an arm 89 which is adjustably mounted upon the slide bar 30 in similar manner to the arm 37 of the first embodiment. The block 88 may be made resilient in character and is connected with the arm 89 through a slot 90 in the table 15 for permitting its adjustment movement. The bar 30 is provided with a roller 31 as in the previous embodiment for engagement with and movement by the lever 32 which derives its operative movement from the engagement, due to the spring 35, of its ball end 34 with the fixed cam 91 (Fig. 11) secured to the fixed side frame member 13.

The operation of this embodiment is as follows:

The sheet S delivered to the table 15 from the right-hand side thereof in the direction of the arrow d, passes over the stop device 62 and encounters the other stop device 61 with its head end. The sheet S then rests upon the table 15 somewhat as shown in Figs. 7 and 8. Upward movement of the arms 10, 11 now commences to bring the saddle into stitching position. Such movement first causes movement of the right-

hand stop device 62 towards the left by reason of the movement imparted to the slide bar 30 by the engagement of the ball-end 34 of the lever 32 with the cam 91. The block 88 of the stop device 62, therefore, engages the tail end of the sheet S and thereby moves the latter bodily along the table to bring the head end of the sheet into abutting relationship with the right-hand face of the block 65, passing, as it does so, beneath the guide flap 72 and the ball 71. As this position is reached the thrust bar 76 is moved to the right by reason of the engagement of the roller 77 thereon with the fixed cam 78, and in consequence the bolt 82 is brought into engagement with the block 65 to move the latter to its normal (right-hand) position if for any reason it has not already been moved into such position by the springs 66.

The above movement of the bar 76 and the block 65 causes the engagement of the surface 85 of the clamping plate 85 with the extension 87 of the clamping lever 68 to raise the latter to effect clamping of the sheet S between the roller 69 and the ball 71. As soon as the sheet is thus effectively clamped the stop device 62 is again moved to the right by the action of the cam 91 upon the lever 32 associated with the slide bar 30.

The arms 10, 11 continue to rise until the sheet-supporting table 15 and the sheet S thereon are located in stitching position, the sheet still being held securely clamped against displacement along the table by means of the roller 69 and ball 71. After stitching, the arms 10, 11 and the table 15 commence their downward and return movement, the sheet S being readily withdrawn from between the roller 69 and ball 71 owing to the manner of mounting of the former. Upon arrival at its original and lowered position the table 15 is ready for the feeding of the next sheet and the repetition of the cycle of operation.

The further modified construction shown in Figs. 12 to 22 will now be described. In this embodiment the sheet-supporting table 15 of the saddle is carried, as before, by supporting arms 10, 11 pivotally mounted for swinging movement about the shaft 12 journaled in the side frame members 13, 14 and under the control of cam discs 22 having cam grooves 21 receiving the cam follower rollers 19 of the extensions 20 of the arms 10, 11. The stitching mechanism is indicated generally at 16 and as the precise construction of the machine generally can follow any known or convenient form and does not form part of the invention it will not be further described.

The sheet-supporting table 15 is provided with a registering and clamping device 100 comprising a plate 101 adjustably secured to the table 15 by means of a set screw 102 passing through a slot 103 in the plate into any one of a number of tapped holes 104. To the plate 101 is secured a block 105 guided within a channel 106 formed in a bar 107 which is slidably mounted in the table 15 in similar manner to the bar 76 of the last described embodiment. The block 105 is provided with a laterally projecting tongue 108, the position of which can be adjusted with respect to the table 15 in unison with the plate 101 and block 105.

A stop plate 110 is slidably mounted upon the face of the table 15 by means of guide rods 109 slidable in apertures formed in the plate 101 and by means of projections 111 slidable in grooves 112 in the table. The stop plate 110 is provided with a guide flap 113. Springs 114 surround each guide rod 109 between the plate 101 and the

plate 110 and act to urge the latter towards the right (Figs. 14 to 17) as far as the enlarged ends 115 of the rods 109 will allow.

Also carried by the plate 101 is a lug 116 to which is pivotally secured a rocking lever 117 the movement of which is limited in each direction by stops 118, 119. This lever 117 is provided with a lug 120 carrying a pin 121 engaging within a slot 122 formed in a projecting portion of a plate 123. This latter plate 123 is carried upon the upper surface of the slide bar 107, being clamped thereto in an adjustable manner by means of a bolt 124 entering a block 125 shaped to fit within the bar 107.

15 Mounted upon the plate 123 is a blade spring 126 to which is secured a block 127 retaining a ball 128 in a manner permitting free rotation of the latter but preventing its displacement. The block 125 is provided with a dependent lug 129 to which is pivoted a clamping lever 130. The connection between the latter lever and the lug is effected by the provision of two ears 131 (Figs. 18, 19) disposed one on each side of the lug and apertured to receive a pin 132. The clamping lever 130 is provided with an extension 133 adapted to engage beneath the tongue 108 so as to rock the lever in an anticlockwise direction while the lever is also provided at its right-hand end with a roller 134 carried in a recess 135 upon a pin 136. This roller is located immediately beneath the ball 128 and co-operates with the latter in similar manner to the arrangements of the previous embodiments. The clamping lever is normally urged in a direction separating the ball from the roller by a spring 137 located within a recess 137a in the clamping lever.

20 The bar 107 is provided with a roller 148 at its left-hand end (Figs. 13 and 17). This roller is maintained in engagement with a cam member 20 to which is fixed to a stationary part of the machine frame by means of a spring 150.

25 The construction of the registering and clamping device 100 is such that the stop plate 110 and the clamping means constituted by the ball 128 and roller 134 on lever 130 can be moved simultaneously to adjust the mechanism to different sized sheets. The correct adjustment position for the clamping means for any given position of the stop plate 110 and carrier plate 101 is immediately determined by the limiting stops 118, 119 for the lever 117.

30 Carried above the stitching saddle is a sheet-braking device indicated generally by the reference numeral 138. This device is adjustably mounted upon a bar 139, extending transversely across the machine, in a manner permitting adjustment of the position at which said braking device engages the sheets as well as the pressure exerted thereby upon said sheets.

35 In the example shown this braking device has the form of a rotatable brush wheel 140, the bristles of which are inclined as shown in Fig. 20 in the direction of incidence of the sheets so that they readily pass beneath said wheel when travelling on to the table 15. The wheel 140 is provided with a one-way clutch, e. g. a ball clutch or ratchet device for rotation about an axle pin 141. The brush wheel is preferably provided with ball-bearings and is readily rotated by the engagement of the incoming sheet during movement in the feeding direction of the latter but, due to the disposition of the bristles and the provision of the one-way clutch, is not rotatable in the reverse direction and in consequence considerably modi-

fies any rebound movement of the sheet from the stop plate 110.

The braking device 138 is arranged to participate in the movement of the table only to a slight extent so that during the swinging-in movement of the stitching saddle during which the registration of the sheet is effected, the latter is only initially acted upon by the device 138. For the purpose of allowing this small amount of swinging movement the bar 139 on which the brush carrier 142 is mounted is carried in guide members 143 slidable in arcuate slots 144 formed in plates 145 secured to fixed parts of the machine structure. The movement of the bar 139 is controlled by link mechanism 146 driven by the main drive shaft 23 of the machine so that the bar swings with the saddle but gradually lags behind it whereby a stroking action of the brush wheel 140 upon the sheet is obtained, to cause the latter to be firmly seated against the apex edge 25 of the table 15.

The manner of operation of this embodiment is as follows: The sheet S advanced e. g. at high speed from the feed table 58 by the feed rollers 59, 60, is introduced with the head end leading on to the table 15 in the direction of the arrow e. The sheet first travels beneath the brush wheel 140, the latter rotating freely, and then encounters the stop-plate 110 to displace it somewhat against the action of the springs 114 which subsequently act to restore the stop-plate to its original or rest position. Any tendency of the sheet to rebound is checked by the operation of the braking device 138.

In this position (shown in Figs. 14 and 15) which the sheet now occupies the clamping lever 130 is still lowered and the roller 134 therefore separated from the ball 128, due to the action of the spring 137.

Movement of the arms 10, 11 now takes place to move the table 15 from the lowered sheet-receiving position shown in Fig. 12 to the raised or stitching position beneath the mechanism 16. As the brush wheel 140 is moved by the link mechanism 146 at a slower rate than the table 15, said wheel acts upon the sheet S to stroke the latter flat against the surface of the table and to seat the fold of the sheet firmly against the apex 25 of the table. During the upward movement of the saddle the roller 148 of the slide bar 107 engages the fixed cam 149 and at a predetermined instant the said bar commences to move against the action of spring 150 towards the left and to carry with it the parts 125, 128, 130 and 134 carried by the plate 123. In consequence of this movement of the plate 123 and the arm having the slot 122 therein, the lever 117 is rotated about its pivot to engage the protuberance 109 upon the stop plate 110 and thereby to urge the latter towards its right-hand and proper registering position and to lock such stop plate in that position.

Simultaneously the extension 133 of the clamping lever is moved beneath the tongue 108 of the stationary block 105 and thereby causes the rocking of the clamping lever 130 to bring the roller 134 towards the ball 128 thereby effectively gripping the sheet S therebetween. The sheet S, thus clamped, now also partakes in the leftward movement imparted to the slide bar 107 by the cam 149 acting upon the roller 148 and is eventually brought with its head end in positive contact with the now locked stop plate 110 and registered thereagainst.

The roller 134 and ball 128 are held in their

clamping position until after the sheet has been brought into stitching position and stitched. Return movement of the arms 10, 11 and the table 15 towards the lowered position causes the withdrawal of the sheet S from between the roller 134 and the ball 128 in a direction transverse to that in which it was originally fed, a movement permissible by the manner of mounting the roller.

The embodiments shown and described are 10 all book-stitching machines of the swinging saddle type and employing thread-stitching mechanism but it will be clear that the invention may equally well be employed with other forms of sheet-handling machines. Similarly the arrangements described may be provided with the various auxiliary mechanisms known in the art for facilitating the operation thereof, e. g. devices for aligning the fold of the delivered sheet with the apex of the saddle and for making the delivered sheet lie flat upon the table; since these do not form an essential part of the invention they are not shown.

We claim:

1. The method of registering paper sheets or signatures in book-stitching machines which 25 comprises the steps of engaging the tail end of the sheet or signature disposed upon a feed table to move it so as to bring its head end into engagement with a sheet fixing stop upon said table thereby to register the sheet, clamping said head end in such registered position upon said feed table, disengaging the tail end of said sheet and then conveying the sheet while clamped upon said feed table to the stitching position and stitching it.

2. For the purpose of registering paper sheets or signatures in a paper sheet-handling machine, a sheet-supporting and conveying table, movable from a sheet-receiving position to a sheet-delivery position, a movable registering stop upon said table, means for bringing a sheet or signature received upon said table into abutment with said stop to register it and clamping means operable to maintain said sheet in registered position against said stop during movement of said stop and during movement of said table to the sheet-delivery position.

3. In a book-stitching machine for the purpose of registering paper sheets or signatures before stitching, a sheet-supporting and conveying table movable from a sheet-receiving position to a sheet-stitching position, a displaceable registering stop upon said table, a sheet-engaging device movable on said table to shift a sheet or signature received upon said table into abutment with said stop to register it, a movable clamping member for engaging and holding said sheet in abutment with said stop during displacement thereof and cam means operable during the movement of the table from its sheet-receiving position to its sheet-stitching position for moving said clamping lever into its sheet-engaging and holding position during such movement.

4. Sheet-registering mechanism for a book-stitching machine having a sheet-supporting and conveying table movable from a sheet-receiving position to the sheet-stitching position comprising a registering stop upon said table, means for moving the sheet into registered position against said stop, a clamping lever movable into and out of clamping engagement with said sheet in the registered position, a fixed cam carried by the machine frame and mechanism carried by the table and operable by engagement with said cam during movement of the table towards the

sheet-stitching position for causing movement of said clamping lever into its clamping position.

5. Sheet-registering mechanism for a book-stitching machine having a swinging sheet-supporting table movable from a sheet-receiving position to a sheet-stitching position and comprising a registering stop upon said table, a sheet-engaging member movable along said table for moving the sheet into registered position against said stop, clamping means for holding said sheet in its registered position against said stop, said clamping means comprising a ball disposed upon one side of the sheet and a roller having its axis of rotation disposed transversely to the direction of swinging movement of the sheet-supporting table on the other side of the sheet and means for urging said ball and roller towards one another to clamp the sheet therebetween during the swinging movement of the sheet-supporting table and during the stitching operation.

6. Sheet-registering mechanism for a book-stitching machine having a sheet-supporting table movable from a sheet-receiving position to a sheet-stitching position and comprising a resiliently displaceable sheet-registering stop carried upon said table for engagement with one end of the sheet fed to said table, means operatively connected with the driving shaft of the machine for returning said stop to a predetermined position subsequent to the sheet-feeding operation, clamping means for engaging said sheet to hold it in given position relative to said stop and mechanism controlled by the operation of the machine for moving said clamping means into sheet-engaging position during movement of the table to the stitching position and subsequent to the operation of said stop-returning means.

7. Sheet-registering mechanism for a book-stitching machine as claimed in claim 6 in which said stop-returning means serve to lock the sheet-registering stop in the predetermined position during the swinging movement of the table and during the stitching operation.

8. In a book-stitching machine having a sheet-supporting table movable between a position where sheets are received thereon and a position where such received sheets are stitched, the provision of sheet-registering mechanism comprising a stop carried upon said table for engaging the head end of the fed sheet, a second stop carried upon said table for engaging the tail end of said sheet, controllable sheet-clamping means associated with said first stop for clamping the sheet in fixed relation to said first stop, mechanism operatively connected with the main driving shaft of the machine for moving the second stop first towards the first stop so as to bring the head end of the sheet into proper engagement therewith and then away from said first stop and further mechanism operatively connected with the main driving shaft of the machine for controlling said sheet-clamping means to place such means in non-gripping condition during the movement of the second stop to bring the head end of the sheet into engagement with the first stop and to place such sheet-clamping means in effective gripping condition during subsequent movement of the sheet-supporting table towards the stitching position.

9. In a book-stitching machine for the purpose of sheet-registration the combination of a swinging sheet-supporting saddle movable from a sheet-receiving position to a sheet-stitching position, a slide bar carried by said saddle, a

sheet stop adjustably connected to said slide bar, a second slide bar carried by said saddle, a second sheet stop adjustably connected to said second slide bar, a sheet-clamping lever carried by said second stop and normally held in non-clamping position, a cam surface fixed to the saddle and engageable with said sheet-clamping lever to move it to sheet-clamping position, two cams fixed to the frame of the machine and engaged by separate followers carried by the sheet saddle, means operatively interconnecting one of said cam followers with said first slide bar whereby the first stop is moved towards the second stop during swinging movement of the saddle towards the stitching position to bring the fed sheet into abutment therewith and means operatively interconnecting the second of said cam followers with the second slide bar whereby the second stop and the sheet in contact therewith are moved during the swinging movement of the saddle towards the stitching position towards the first stop to bring the sheet-clamping lever into engagement with said fixed cam means and thereby to move it into its sheet-clamping position.

10. Sheet-registering mechanism for a sheet-handling machine having a sheet-supporting table movable from a sheet-receiving position to a sheet-delivery position and comprising a sheet stop carried by said table, a controllable sheet-clamping device movably mounted on said table and mechanism operatively connected to the driving means for the machine for controlling said sheet-clamping device to grip the sheet and for moving said clamping device subsequently to the gripping of said sheet to bring the sheet into engagement with said sheet stop and to maintain said sheet in gripped condition thereagainst during movement of the table to the stitching position.

11. Sheet-registering mechanism for a paper sheet-handling machine having a sheet table movable between a sheet-receiving position and a sheet-delivery position, comprising a stop carried by said table in the path of the sheets fed to such table, braking means operable to enable free feeding of sheets to the table and for restricting rebound movement of the fed sheet from said stop and sheet-clamping means operatively connected to the driving means of the machine for engaging and clamping said sheet during movement of the table to the delivery position.

12. Sheet-registering mechanism as claimed in claim 11 in which said braking means comprises a brush wheel resting lightly upon the sheet disposed upon the sheet-supporting table and pivotally mounted by means of a one-way rotation clutch device permitting its rotation only in the feeding direction of the sheets.

13. Sheet-registering mechanism for a paper sheet-handling machine as claimed in claim 11 in which said braking means are carried by adjustable mounting means permitting the control of the braking pressure exerted thereby and the position of the point of contact thereof with the sheet.

14. Sheet-registering mechanism for a book-stitching machine having a swinging sheet saddle comprising a sheet stop carried by said saddle, means for registering a folded sheet fed to said saddle against said stop, clamping means operative during the swinging movement of said saddle to maintain said sheet in registered position against said stop, a brush lightly engaging the surface of said table and mechanism for mov-

13

ing said brush with said saddle over part of its swinging movement but at a different speed relative thereto whereby the sheet on said saddle is smoothed and the fold of the sheet registered with the apex edge of said saddle.

15. Sheet-registering mechanism for a book-stitching machine having a sheet-supporting table movable from a sheet-receiving position to a sheet-stitching position and comprising a normally fixed registering stop carried in an adjustable manner upon said table, a sheet-clamping device adjustably carried upon said table adjacent said stop and operable to clamp the sheet fed to the table during movement of the latter from the sheet-receiving to the sheet-stitching position and means interconnecting said registering stop and said sheet-clamping device for enabling simultaneous adjustment thereof to accommodate different sized sheets and for holding said sheet in fixed relation to said stop.

16. The method of registering paper sheets or signatures in paper sheet-handling machines which comprises the steps of bringing the sheet to registration against a stop, holding said sheet in fixed relation to said stop and displacing said sheet and stop during its conveyance to a position for further treatment.

17. The method of registering paper sheets or signatures in book-stitching machines which in-

14

cludes the steps of bringing the sheet to be stitched to registration against a stop, holding said sheet in fixed relation to said stop, displacing said stop and sheet to registered position, and retaining the same in said position until after stitching.

18. A method of registering paper sheets or signatures on a sheet supporting and conveying table, comprising feeding a sheet onto said table, displacing said table to convey the sheet, displacing a stop into engagement with the sheet, holding the sheet in fixed relation with respect to the stop and displacing the stop and sheet to a registered position.
